PYROLYSIS OF SECONDARY-BUTYLBEN-
ZENE DERIVATIVESRobert R. Dreisbach, Midland, Mich., assignor to
The Dow Chemical Company, Midland, Mich., a
corporation of MichiganNo Drawing. Application November 12, 1937,
Serial No. 174,221

9 Claims. (Cl. 260--668)

This invention concerns the pyrolysis of a benzene derivative having the general formula

wherein X and Y each represent hydrogen, halogen, or an alkyl radical and n and n' are integers having a sum not exceeding 5. For convenience, 10 compounds having said general formula are hereinafter referred to generically as "secondary-butylbenzene compounds." The invention particularly concerns the simultaneous production of styrene and allyl benzene by pyrolysis of secondary-butylbenzene.

It is well known that ethylbenzene and certain other alkyl benzenes may be pyrolyzed to produce styrene, but insofar as I am aware, secondary-butylbenzene has not previously been pyrolyzed 20 nor has the formation of an allyl benzene by pyrolysis of any alkyl benzene heretofore been known.

I have now found that a secondary-butylbenzene compound having the above general formula 25 may be pyrolyzed to obtain a vinyl aromatic compound and an allyl aromatic compound, and that the respective yields of these two types of products are at least partially dependent on the temperature at which the pyrolysis is carried out 30 and may be controlled. More specifically I have discovered that secondary-butylbenzene may be pyrolyzed to produce styrene and allyl benzene and, other operating conditions being constant, that the yield of styrene increases and that allyl 35 benzene decreases as the pyrolysis temperature is raised. I have further discovered that activated charcoal catalyzes the reaction for the formation of styrene and enables the latter to be produced in good yield at pyrolysis temperatures much 40 lower than are required to obtain the same yield of styrene in the absence of such catalyst. The invention, then, consists in the method herein-after fully disclosed and particularly pointed out in the claims.

45 The pyrolysis is carried out at temperatures above 450° C. by heating the butylbenzene compound and cooling it before excessive carbonization can occur. The period during which the compound may be maintained at a pyrolyzing 50 temperature depends of course upon the maximum temperature employed and the particular compound under treatment, but for any given compound the permissible period of heating decreases as the pyrolysis temperature is raised. 55 Theoretically, the pyrolysis could be carried out

at very high temperatures, e. g. 1200° C., by employing a shock mode of heating wherein the compound would be heated and cooled almost instantaneously, but it is usually impractical to operate at temperatures above 950° C. It is 5 inadvisable to heat the secondary-butyl compound at temperatures above 750° C. for more than 0.1 second, since otherwise carbonization and tar formation may occur to objectionable extent, but longer periods of heating may be employed and are usually required when operating 10 at lower temperatures.

The pyrolysis may be carried out in any of the usual ways, e. g. by passing a secondary-butylbenzene compound alone or in admixture with a 15 gaseous diluent such as steam or carbon dioxide through an externally heated tube or a bath of lead or other molten metal, but as hereinbefore stated care must be taken to heat and cool the 20 vapors with sufficient rapidity to avoid excessive carbonization. In practice, the pyrolysis is preferably carried out according to the general method for pyrolyzing alkylated aromatic hydrocarbons set forth in my co-pending application, 25 Serial No. 151,457, filed July 1, 1937, of which this application is a continuation-in-part. This 30 preferred mode of operation, described below, permits the desired products to be formed in higher yield than I have found possible by the usual pyrolytic methods, without appreciable carbonization or tarring of the reaction mixture.

A liquid or vaporized secondary-butylbenzene compound and superheated steam are passed 35 continuously into admixture with one another, the steam being employed in the proportion and at the temperature required to attain the reaction 40 temperature and furnish the heat of pyrolysis. Usually, between 7 and 10 parts by weight of steam superheated to a temperature between 600° and 1000° C. is used per part of the secondary-butylbenzene compound, but the steam may 45 of course be employed in other proportions and at other temperatures. The mixture is passed through the reaction tube at a rate permitting substantial pyrolysis but sufficient to prevent appreciable carbonization or tar formation. As 50 hereinbefore stated, this rate varies somewhat depending on the particular secondary-butyl compound under treatment and the temperature employed. In general, however, best results are obtained when the rate is such that the vapors are maintained at a pyrolysis temperature of 450° C. for not more than 2 seconds, at 750° C. for not more than 0.1 second, and at 900° C. for not more than 0.03 second. The mixture issuing from the 55

tube is cooled rapidly, e. g. by contact with water or by passage through suitable heat exchangers or condensers, to a temperature below 450° C. and the cooling is continued to condense the aromatic components of the mixture. The organic condensate is then distilled, preferably under vacuum, to separate the vinyl- and allyl-type products. Any unreacted secondary-butylbenzene compound recovered in the distillation is returned to the pyrolysis.

The following examples illustrate certain ways in which the principle of the invention has been applied, but are not to be construed as limiting the invention:

15

Example 1

One part by weight of vaporized secondary butylbenzene and about 8.5 parts of steam superheated to about 880° C. were passed simultaneously into a reaction chamber to form a mixture having a temperature of about 550° C. The mixture passed through the reaction chamber and into suitable coolers and condensers at such rate as to be maintained at 550° C. or thereabout for only about 0.5 second. The so-treated mixture was cooled sufficiently to condense the aromatic components thereof. There was obtained 0.96 part by weight of organic condensate containing approximately 12.8 per cent by weight of allyl benzene and 87.2 per cent of unreacted secondary-butylbenzene.

Example 2

Secondary-butylbenzene was vaporized and passed into admixture with about 8.5 parts by weight of steam which had been superheated sufficiently so that the mixture formed was of a temperature of about 725° C. The mixture was cooled to below 700° C. within about 0.05 second after formation and the cooling was continued to condense the aromatic components of the mixture. The organic condensate was a clear brownish liquid containing approximately 67.4 per cent by weight of unreacted secondary-butylbenzene, 22 per cent of allyl benzene, 1.7 per cent of benzene, and less than 1 per cent of styrene.

Example 3

Secondary-butylbenzene was pyrolyzed at a temperature of about 730° C. by admixture with superheated steam, the procedure being similar to that described in Example 2, except that the pyrolysis mixture was passed, immediately after formation, through a bed of granular activated charcoal at such rate as to be contacted with the charcoal for approximately 0.08 second. The vapors issuing from the charcoal were promptly cooled sufficiently to condense the aromatic products. The organic condensate contained approximately 33 per cent by weight of unreacted secondary-butylbenzene, 29.7 per cent of styrene, 23 per cent of allyl benzene, and minor proportions of benzene and ethylbenzene.

65

Example 4

A mixture of ortho-chloro-secondary-butylbenzene and meta-chloro-secondary-butylbenzene was pyrolyzed at a temperature of about 550° C. by admixture with superheated steam, the procedure in carrying out the pyrolysis and condensing the product being similar to that described in Example 1. The organic condensate was a slightly colored liquid containing about 79 per cent by weight of unreacted chloro-butylbenzenes, 8 per cent of ortho- and meta-chloro-

allyl benzenes, and minor proportions of by-products such as chloro-isopropyl benzenes, chloro-styrenes, etc.

Example 5

A mixture of isomeric ethyl-secondary-butylbenzenes was pyrolyzed at a temperature of about 780° C. by admixture with superheated steam and the aromatic products were condensed, the procedure being similar to that set forth in Example 10. The liquid organic condensate contained approximately 10.2 per cent of unreacted ethyl-secondary-butylbenzenes, 44.8 per cent of ethyl-allylbenzenes, 22.8 per cent of ethyl-vinylbenzenes, 6.2 per cent of styrene, and minor proportions of by-products such as diethylbenzene, ethylbenzene, etc.

Other secondary butylbenzene compounds may be pyrolyzed in accordance with the invention to obtain nuclear substituted allyl benzenes. For instance, secondary - butyl-3,5 - dichlorobenzene may be pyrolyzed to obtain allyl-3,5-dichlorobenzene, secondary-butyl-3-bromo-benzene may be pyrolyzed to obtain allyl-3-bromobenzene, secondary-butyl-3-chloro-5-methylbenzene may be pyrolyzed to obtain allyl-3-chloro-5-methylbenzene, etc. In pyrolyzing such relatively complicated secondary-butylbenzene compounds numerous by-products are frequently obtained. These by-products usually include styrene homologues and analogues useful in preparing synthetic resins.

The expression "allylbenzene compound" as hereinafter employed refers generically to allyl benzene and certain derivatives thereof preparable by the pyrolysis of nuclear substituted secondary butyl benzenes wherein the nuclear substituents are halogen or lower alkyl groups.

Other modes of applying the principle of the invention may be employed instead of those explained, change being made as regards the method herein disclosed, provided the step or steps stated by any of the following claims or the equivalent of such stated step or steps be employed.

I therefore particularly point out and distinctly claim as my invention:

1. The method which comprises pyrolyzing secondary-butylbenzene to obtain allyl benzene.
2. In a method for producing allyl benzene, the step of pyrolyzing secondary-butylbenzene at a temperature not exceeding 800° C.
3. In a method for producing allyl benzene, the step of pyrolyzing secondary-butylbenzene at a temperature not exceeding 800° C. by admixing the secondary-butylbenzene with steam superheated sufficiently to attain the pyrolysis temperature and promptly thereafter cooling the mixture.
4. The method which comprises admixing secondary-butylbenzene and superheated steam to obtain a mixture having a temperature between 450° and 800° C., maintaining the mixture within said temperature range for a period sufficient to permit pyrolysis of the secondary-butylbenzene but not appreciable carbonization and cooling the mixture.

5. The method which comprises pyrolyzing secondary-butylbenzene in the presence of activated charcoal.

6. The method which comprises pyrolyzing secondary-butylbenzene by admixing the same with steam superheated sufficiently to attain a pyrolysis temperature, passing the freshly formed pyrolysis mixture into contact with activated

charcoal and promptly thereafter cooling the mixture.

7. In a method for making an allylbenzene compound the step which consists in pyrolyzing a compound having the general formula:

10 wherein X and Y each represents a substituent selected from the group consisting of hydrogen, halogen and lower alkyl substituents and n and n' are integers having a sum not exceeding 5.

8. In a method for making an allylbenzene compound the steps which consist in pyrolyzing a compound having the general formula:

20 wherein X and Y each represents a substituent selected from the group consisting of hydrogen, halogen and lower alkyl substituents, and n and

n' are integers having a sum not exceeding 5, by admixing said compound with steam superheated sufficiently to attain the pyrolysis temperature and cooling the mixture.

9. In a method for making an allylbenzene compound the steps which consist in pyrolyzing a compound having the general formula:

wherein X and Y each represents a substituent selected from the group consisting of hydrogen, halogen and lower alkyl substituents and n and n' are integers having a sum not exceeding 5, by 15 passing the compound into admixture with a current of steam superheated sufficiently to attain the pyrolysis temperature, passing the freshly formed pyrolysis mixture into contact with activated charcoal, and promptly thereafter cooling 20 the mixture.

ROBERT R. DREISBACH.
